UNITED STATES PATENT OFFICE

HUGO BEZNER, OF GROSSINGERSHEIM, GERMANY

SHIRT COLLAR

Application filed August 23, 1927, Serial No. 214,882, and in Germany June 30, 1927.

The invention relates to shirt collars. So-called turn-down and double shirt collars, when starched, are liable to the defect that it is difficult to slip the necktie between the body ⁵ of the collar and the flap, owing to the outer and inner portions having been pressed too tightly together by the ironing and subsequent rounding or shaping process.

According to my invention the collar is provided, preferably on the inside, with a mark, which may be in the form of a full or dotted line or a seam or the like, so positioned that if the ironer spreads or pulls the collar so that this mark forms a straight line ¹⁰ in the course of ironing the fold of the collar assumes just that bend which is required so that when the collar is given its proper curvature there will be a convenient clearance between the inside and outside portions.

¹⁵ The invention is illustrated in the accompanying drawing, in which

Fig. 1 shows the collar spread out.

Fig. 2 is a section showing the folds of the collar in the position assumed after having ²⁰ been ironed in accordance with the present invention.

The collar, according to my invention, comprises a neckband *a* and outer or body portion *b* and has on said portion *a* a mark in the ²⁵ form of a line or seam *d*. Before ironing the collar the laundry operative spreads it so that this line is quite straight, using a ruler if required, and the fold *e* then acquires just the right curvature.

³⁰ I may print the mark, or provide it in any other convenient manner, but prefer to use a seam, because this is visible on both sides, and is conspicuous if colored, non-fading thread is used.

³⁵ Figure 2 shows a starched collar which has been ironed with the aid of the guiding line or seam shown at *d* in Figure 1, and the finished collar having sufficient clearance *c* to accommodate a necktie easily.

⁴⁰ What I claim as my invention and desire to secure by Letters Patent of the United States is:—

⁴⁵ 1. A turn-down starched collar including a body portion, a neckband portion, and a visible mark on one of said portions extending

substantially the length of the collar and longitudinally thereof, said mark being formable into a straight line before the collar is ironed to indicate the proper position in which the portions of the collar are to be ⁵⁵ ironed in order to provide a space between said portions, after the folding thereof, through which a necktie is easily slidable.

2. A turn-down starched collar including a body portion, a neckband portion, and a mark on said neck band portion visible from both sides thereof and extending substantially the length of the collar and longitudinally thereof, said mark being formable into a straight line before the collar is ironed to indicate the proper position in which the portions of the collar are to be ironed in order to provide a space between said portions, after the folding thereof, through which a necktie is easily slidable. ⁶⁰

3. A turn-down starched collar including a body portion, a neckband portion, a folding line between said portions of arcuate formation when said portions are laid out flat, and a visible mark on said neckband portion ⁶⁵ which, when formed into a straight line, before ironing the collar, will so position said folding line that, after the collar has been ironed with said mark held in a straight line and said portions have been folded on said ⁷⁰ folding line, a space will be formed between said portions through which a necktie is easily slidable.

In testimony whereof I have affixed my signature. ⁷⁵
